UNITED STATES PATENT OFFICE.

HEINRICH BASCHY, OF HAMBURG, GERMANY.

APPARATUS FOR CLEANING METAL WALLS, TUBES, FLOORS, AND THE LIKE.

1,404,082.

Specification of Letters Patent. Patented Jan. 17, 1922.

Application filed June 25, 1915. Serial No. 36,375.

(GRANTED UNDER THE PROVISIONS OF THE ACT OF MARCH 3, 1921, 41 STAT. L., 1813.)

To all whom it may concern:

Be it known that I, HEINRICH BASCHY, a citizen of Hamburg, and residing at Hamburg, in the German Empire, have invented 5 certain new and useful Improvements in Apparatus for Cleaning Metal Walls, Tubes, Floors, and the like, (for which I have filed application in Germany, Sept. 16, 1914,) of which the following is a specification.

10 This invention relates to apparatus for cleaning metal walls, tubes, floors and the like and more particularly for removing the scale or incrustations of boilers. This apparatus is similar to such cleaning devices 15 in which a disk like body is provided with implements either fixed or rotatable or otherwise movable, for instance chisels, cutting rolls or rose bits, which project beyond the rim of the disk, and on the rotation of 20 the disk loosen or remove the scale or the like.

When using these known devices particular care must be taken that the disk body is not held at an acute angle but must always 25 be held at right angles to the surface to be cleaned, for if held at an acute angle the implements are apt to cut holes into the walls to be cleaned and the device will be pulled out of its working position. Even 30 if the workman succeeds in avoiding such a mishap the special care which has to be taken will be a hindrance to a speedy working, and therefore a loss of time is the result. To avoid these drawbacks according 35 to the present invention the implements are so positioned or journaled on the disk that they rotate not only about their axes in a plane parallel to the disk but also can turn or adjust themselves in all directions trans- 40 versely to the said plane. Consequently by such lateral rotatability of the implements in all directions they automatically position themselves into the most favorable position, and therefore cannot catch the wall to be 45 cleaned in any injurious manner, no matter whether the disk-like body is held at right angles to the wall or not. The present apparatus also enables the cleaning of parts, which are otherwise difficult to be got 50 at, for instance corners, rivetheads and the like. The handling of the apparatus is thus considerably simplified and facilitated and the operation is thus essentially improved.

A very important advantage of the pres-

ent invention consists in providing the cutting implement with rollers having outer sharp cutting rims, which are particularly effective, but which if rotatable about a fixed axis would cut into the wall with great power, when the carrying disk is rotating at 60 an acute angle to the wall operated upon. The effect of the cutting rollers being adapted to turn in all directions is particularly good, when they are slidable within the disk body in such manner, that on the 65 quickly rotating body a flinging action of the cutting rollers has the effect of blows.

In the drawing Figure 1 shows the apparatus in a side view partly in section and Fig. 2 is a top plan view.

The body consists of two disks *b* fixed parallelly and at a certain distance from one another, to a shaft *a*, which can be rotated in any suitable manner; for instance it may be attached to the known flexible 70 shaft, not shown. Between the disks *b*, cutting rollers *c* are journaled each having thus an annular preferably V-shaped groove *c*¹ thus forming two sharp cutting edges on the rollers. There rollers are provided on 75 both sides with hemispherical projections *d*, which form studs, the common central line of which form the axis for the cutting rollers. By these hemispherical studs *d* the cutting rollers are journaled between the 80 disks *b*, and have the effect that they can rotate in all directions, so that no matter at what angle the disks *b* are held, the cutting rollers will adjust themselves within the limits formed by the disks *b* themselves. 85

When the cutting rollers *c* project beyond the rim of the disks the cutting edges clean the wall operated upon, and they will adjust themselves automatically into proper position, when the disk body is held obliquely to the wall or when the apparatus hits against a rivethead on its reciprocating motion or when any other projecting part is struck by the rollers.

Each cutting roller *c* is guided by the 100 hemispherical studs *d* in suitably shaped grooves *e* on the inner surface of the disks *b*. These grooves *e* are curved to a spiral line leading towards the centre of the disks *b*, and when the cutting rollers *c* are hurled 105 outward so that their hemispherical studs lie at the outer end of the grooves and the cutting edges project beyond the rim of the

disk body. By reversing the direction of rotation of the disks *b* the rollers *c* will be drawn inward to the inner ends of the grooves.

5 In operation the cutting rollers are hurled against the surface to be cleaned having a hammer like action against the same and rebounding into the inner part of the disk-like body.

10 It is to be understood, that the cutting implements need not have the shape of cutting rollers as shown, but may be constructed in any other suitable manner.

I claim:

15 1. An apparatus for cleaning metal walls, tubes, floors and the like, comprising a plurality of circular rotatable and universally movable cutters, a rotatable carrier for the cutters consisting of two disks having

curved grooves in the opposite faces thereof 20 within which the cutters are movably journaled, said grooves being arranged eccentric to the axis of the carrier.

2. An apparatus for cleaning metal walls, tubes, floors and the like, comprising a pair 25 of parallel disks having grooves in their opposing faces circular in cross section and extending from near the axes of said disks to near the peripheries thereof eccentric to the axes of said disks, and disk-like cutters 30 having hemispherical journals on each side arranged symmetrically to the cutting edges of the cutters and adapted to slide and roll in said grooves from end to end.

HEINRICH BASCHY.
